UNITED STATES PATENT OFFICE

KARL C. PARKHURST, OF WICHITA, KANSAS

TRAFFIC SIGN

Application filed August 14, 1931. Serial No. 557,040.

My invention relates to improvements in a traffic sign.

The object of my invention is to provide a supporting means for the base of a vertically positioned flexible member on which indicia are formed, the said means being adaptable for a plurality of flexible members.

A further object of my invention is to provide a base member having an approach at one side slanting upward from the road bed.

A still further object of my invention is to provide a base supporting means for a flexible panel or a plurality thereof, and means to attach the same to the base member in such a way as to avoid excess compression at the abrupt bending point of the flexible panels.

A still further object of my invention is to provide a base supporting member for flexible panels that may be embedded in the road, and by depressing the road bed at one or both sides of the panel to avoid compression of the panel at the attaching point.

A still further object of my invention is to provide a base member with an approach at one side adapted to work in conjunction with mechanical erecting means for the panels.

A still further object of my invention is to provide a base member having upward slanting approach on one side, and having the vertical portion of the member extending below the road bed, and a depression in the bed to receive a flexible panel when forced downward therein by the wheel of a vehicle, thereby avoiding compression at the clamping point of the panel.

A still further object of my invention is to provide flexible panels interchangeable and having a depressed seat to engage snugly on a like protruding member arranged on the base.

A still further object of my invention is to provide a one way traffic sign positioned in the line of travel on the road bed.

These and other objects will hereinafter be more fully explained, reference being had to the accompanying drawings forming a part of this specification, and in which like characters will apply to like parts in the differ-

ent views, reference with respect to the drawings:

Fig. 1 is an end view partly in section taken on line 1—1 in Fig. 2 illustrating a concrete approach with the base partly embedded. 55

Fig. 2 is a plan view of Fig. 1.

Fig. 3 is an end view of the sign with the base member seated on the surface of the road and an approach integral with the base.

Fig. 4 is a plan view of Fig. 3. 60

Fig. 5 is a view similar to Fig. 1 showing the position of the panel as compressed by a wheel of a vehicle.

Fig. 6 is an elevation of the sign opposite from the approaching side, parts removed 65 for convenience of illustration.

Fig. 7 is an elevation of one of the panels showing the depression at the base.

Fig. 8 is a sectional view taken on line 8—8 in Fig. 7. 70

Fig. 9 is a similar view to Fig. 1 showing the flexible panel hingedly connected to the base and spring actuated.

Fig. 10 is a sectional view taken on line 10—10 in Fig. 9 fragmentarily shown. 75

Fig. 11 is a similar view to Fig. 9 showing a gravity actuating means for the erection of the panel.

Fig. 12 is a sectional view taken on line 12—12 in Fig. 11 fragmentarily shown. 80

Fig. 13 is an end view of a flexible panel positioned in the road bed and depressed along each side thereof, the road bed in section.

My invention herein disclosed consists of 85 a foot member 1 and a vertically disposed portion 2, the upper edge curved as shown at A. Secured to the vertical portion of the base is a flexible panel 3 on one side of which are letters as shown at 4, the said letters being 90 embedded in the panels. The said panels are so arranged that a plurality thereof are distributed along the base member and being spaced apart as shown in Fig. 2, the panels being removable and interchangeable, all of 95 which are secured to the base member by means of a bar member 5, the said bar member being secured to the base by means of bolts spaced therealong as shown at 6, each bolt being positioned between two panels. 100

The above described base member is arranged and designed to be embedded in a road bed by arranging a depression as shown at B, one side of which is vertical while the other 5 side slopes upward to the road bed level. The said base member is placed as shown in Fig. 1. An approach 7 is placed on one side thereof sloping from the road level and extending upward to the top of the base, the same 10 thus arranged is preferably made of concrete, the upper extremity of the base curving toward the approach.

The depression referred to is arranged to receive the flexible panels when forced there-in by a wheel of a vehicle contacting there-with while passing over the same as shown in Fig. 5, and being so arranged the abrupt bending point at the connection will be pro-tected against contact of the wheels of a ve-hicle.

It will be understood that my traffic sign is placed on the right hand side of the road and facing the line of traffic, and each panel will have a letter placed thereon to spell 25 words correctly. For instance in the word "stop", I have arranged four panels, each having a single letter placed thereon spelling the same, and should any one of the panels become damaged by traffic, the same 30 may be removed, by which means I avoid replacement of the entire word.

Spaced along the vertically disposed portion of the base are protrusions 8 and a like indenture 9 is placed near the center of the base portion of each of the panels to receive the same, the indenture being shown in Figs. 7 and 8. This arrangement is to properly position each panel at the time of securing the same to the base member, also to prevent the panel from upward movement from the base should the clamping means become loose.

In Figs. 3 and 4 is shown a modified form which functions in like manner to that previously described. This form of a base member consists of a similar foot and vertical portion as heretofore described, and the curved portion extends forward to the same plane of the base and being so arranged the vehicle will approach and pass over the same as that shown in Fig. 1. This arrangement avoids a depression in the road way. As a means to secure the same to the paving, I have arranged a lip 10 outwardly extending from each end thereof and through which an anchor bolt 11 is inserted into the road bed clamping the same securely thereto. I have also arranged a plurality of bolts 12 spaced along the forward edge of the approach as shown in Fig. 4 for like purpose.

60 A modification with respect to installation is shown in Fig. 13. In this instance we have omitted the base member and simply installed the flexible member into the concrete, and extending from each side thereof is a
65 cavity, the upper corners of which are

rounded as shown at 13. This method will avoid contact at the flexing point of the slab as the base thereof is embedded in the concrete and the upper portion thereof is free to rock in either direction as contact is made by the wheel of a vehicle. Spaced along the lower edge of the slab are a plurality of apertures through which the concrete will inject to avoid withdrawal by repeated flexing of the slab. 70 75

It will be understood that a plurality of panels may be aligned and spaced apart as shown and described for the base plate heretofore described, and in this installation, flexing at the rigid connection is protected. 80

In Fig. 7 is shown by dotted lines reenforcing wires similar to those shown and described in my patent application Serial No. 471,118, filed July 28, 1930, but I do not wish to claim the same broadly in this application, but I wish to illustrate its adaptation to this present method of installation. 85

In Figs. 9 and 11 is shown a similar base member to that shown in Fig. 1, and in each case the indicia panels are hingedly arranged and placed in working relation thereto. Fig. 9 shows the spring actuating means for erection of the indicia panel, while Fig. 11 shows a gravity actuating means for the erection of the panel. By the two latter arrangements the bending of the indicia panel is avoided and in each instant the approaches are the same and the function is the same with respect to the protecting feature of the panel.

While I have shown a continuous panel, with respect to the latter arrangements, with indicia printed thereon, I do not wish to be restricted to the same, as a plurality of members may be employed as heretofore described, and such other modifications may be employed as lie within the scope of the appended claims, and having fully described my invention what I claim as new and desire to secure by Letters Patent is:—

1. In a traffic sign, a base member having a vertical portion and an approach obliquely extending downward to the road bed level, and a flexible indicia plate carried by the vertical portion opposite from the approach and being attached thereto near the lower portion thereof, for the purpose specified. 115

2. In a traffic sign, a base member having a vertical portion and an approach obliquely extending downward to the road bed level, and a flexible indicia plate carried by the vertical portion opposite from the approach and being attached in close proximity to the foot member. 120 125

3. In a traffic sign, a base member having an upper edge portion and means to clamp a plurality of flexible members to the base member, the clamping means spaced downward from the upper edge of the base mem- 130

ber, an approach on the other side of the base member, and means along the upper edge of the base member to form a nosing for the approach, substantially as shown.

- 5 4. In a traffic sign, a base member having a vertically disposed portion, a bar member and means to attach the same to the base, a plurality of flexible panels spaced along the base and being clamped thereto by the bar, the upper edge of which is spaced downward from the top of the base, the base having a protrusion to engage each flexible panel, each panel having an indenture to receive its respective protrusion.
- 10 5. In a traffic sign, a base member comprising a vertically positioned portion and a slanting portion integrally joined, the slanting portion functioning as an approach for a vehicle wheel, a flexible panel and means to clamp the same at the lower extremity of the vertical portion to avoid contact at the bending point by a wheel of a vehicle passing thereover from the approach side.
- 15 6. In a traffic sign, a base member having a portion as an approach obliquely slanting upward from a road bed and terminating with a turned down portion to a vertical position, and a plurality of flexible members, the lower extremities of which are attached to the lower extremity of the vertical portion, and means to clamp the same firmly together, each flexible member having a character thereon confronting the side of
- 20 the approach.
7. In a traffic signal, a panel flexibly disposed, a base structure as vertical supporting means for the panel, said base arranged and positioned in a roadway so that the approaching side for a vehicle is on a higher plane than the other side, by which means the abrupt flexing point of the panel will avoid contact by the wheel of a vehicle passing over the same.
- 25 45 In testimony whereof I affix my signature.

KARL C. PARKHURST.
